UNITED STATES PATENT OFFICE.

JOSEPH P. MORRISON, OF MOUNT CARMEL, PENNSYLVANIA.

ARTIFICIAL TOOTH AND BACKING.

1,170,555.

Specification of Letters Patent.

Patented Feb. 8, 1916.

Application filed August 6, 1915. Serial No. 43,968.

To all whom it may concern:

Be it known that I, JOSEPH P. MORRISON, a citizen of the United States, residing at Mount Carmel, in the county of Northumberland and State of Pennsylvania, have invented certain new and useful Improvements in Artificial Teeth and Backings, of which the following is a specification.

This invention relates to an improved artificial tooth and backing, and one of its objects is to provide an artificial tooth and backing which, while adapted for use in connection with all kinds of teeth, are particularly adapted for application to incisors and canines, to fortify and firmly secure the teeth against breakage or displacement under the peculiar pressures and strains falling upon these teeth in the process of mastication.

A further object of the invention is to provide an artificial tooth and backing adapting the teeth to be applied to plate, crown and bridgework with ease and facility and in an interchangeable manner, so that a damaged tooth may be easily removed and another inserted in its place, the construction also being such as to enable a thin tooth to be used without sacrifice of strength and the tooth to be applied to the denture without exposing the backing at the front.

The invention consists in the features of construction and combination and arrangement of parts more fully hereinafter described and claimed, reference being had to the accompanying drawings, wherein—

Figure 1 is a side elevation of an artificial tooth and backing embodying my invention; Fig. 2 is a vertical longitudinal section of the same; Fig. 3 is a horizontal transverse section; Fig. 4 is a rear perspective view of the tooth detached from the backing; and Fig. 5 is a perspective view of the backing.

Referring to the drawing, 1 designates the body of the tooth, which is usually made of porcelain, and which may represent any form of tooth, but is especially adapted for use as an incisor or canine. As shown, a portion of the lingual surface of this tooth is ~~curved~~, forming the plane vertical abutment face 2 extending longitudinally of the tooth body, and the horizontal transverse shelf or shoulder 3, arranged at right angles to the plane of the face 2. It will be observed that both surfaces 2 and 3 are straight and devoid of curvature, so as to provide for an interlocking connection with

the backing in a novel manner, as hereinafter described.

The body 1 is formed with one or more pin-receiving sockets or recesses 4, two being shown in the present instance, arranged on opposite sides of the longitudinal center of the tooth. These sockets or recesses intersect at their upper ends the shoulder 3 at its point of juncture with the face 2, and thence extend downward and forward at an angle in a direction toward the biting edge of the tooth.

The backing 5, adapted for use in connection with the tooth, comprises a gold or other metallic plate of the same superficial area as the lingual surface of the tooth and having a rib or offset 6 formed upon the buccal surface thereof and adapted to engage and rest upon the shoulder 3. Fixed in the backing and projecting from said shoulder at a downward and forward angle are anchor pins 7 adapted to fit within the sockets or recesses 4 for the purpose of connecting the tooth body with the backing, which is secured in practice to the plate, crown, or bridgework in any suitable or well-known way, the pins being cemented in the recesses and the lingual surface of the tooth cemented to the buccal surface of the backing, as will be readily understood.

It will be observed from the foregoing description that by reason of the construction described the tooth is rendered detachable and interchangeable, so that in event of injury to one tooth another may be substituted by removing the injured tooth and applying a new one to the backing. Also, it will be seen that a firm fastening between the tooth and backing is secured without exposure of the backing from the front of the tooth. Moreover, it will be seen that as the upper and lower portions of the lingual surface of the tooth body, as well as the shoulder 3, are straight or plane surfaced, with the shoulder arranged substantially at right angles to the lingual surface of the tooth body, the abutment surfaces of the tooth and backing are adapted to interlock in such a manner as to give the tooth firm support during the process of mastication, in which the tooth is subjected to direct vertical cutting strains, as well as lateral strains of a kind tending to pull the tooth away from its backing. By making the abutting surfaces straight, and by particularly arranging the shoulder and rib of the

tooth body and backing horizontally and at right angles to the plane of the tooth, the expense of working curved surfaces is avoided, while the angle of resistance is also arranged to give a stronger reinforcement for teeth of the incisor or cupid type. The straight shape of the surfaces also allows the tooth to be used not only for incisors or cuspids, but also for bicuspids or molars, but is particularly valuable in application to incisors or cuspids, where curved abutment surfaces cannot be used without making the tooth and backing of objectionable thickness.

15 The present construction adapts the tooth to be made comparatively thin and the backing correspondingly thin, so that strength and durability will be secured without the tooth being made cumbersome or the backing showing at the front. The present construction also adapts the backing to be extended substantially the full length of the tooth, namely, from the shoulder 3 to the gingival surface, and also and particularly from the shoulder 3 to the occlusal or biting surface, so that a strong backing for the

tooth and anchorage to the bridge work may be obtained under all conditions.

I claim as my invention:

An artificial tooth facing comprising a body having its lingual surface provided with a substantially medial horizontal transverse shoulder, an abutment surface leading from the inner edge of said shoulder toward the gingival surface of the tooth, an abutment surface leading at an angle from the outer edge of the shoulder to the occlusal surface of the tooth, said body being provided with pin-receiving recesses opening through said shoulder, and a backing provided with a corresponding shoulder and abutment surfaces to engage the shoulder and abutment surfaces of the body and having pins projecting from its shoulder to engage said pin-receiving recesses.

In testimony whereof I affix my signature in the presence of two witnesses.

JOSEPH. P. MORRISON.
